DISPLAY DEVICE AND FOLDER

Leroy P. Neher, St. Louis, Mo.

Application December 21, 1936, Serial No. 116,854

5 Claims. (Cl. 40—4)

The present invention relates to display devices and is particularly related to advertising media for use upon tapered neck bottles, such as milk bottles.

5 Display devices of this general type have heretofore been produced; but they have always had the drawback that the advertising space available was necessarily limited, since, to be most satisfactory and practical, the bottle collar must 10 fit within the limits of the tapered neck of the bottle. Ordinarily, bottles of this type have flanges around the upper edges and it is essential that the bottle collar be so formed as to slip over the neck and rest upon the shoulder of the 15 bottle. In order readily to pass over the flanges, the collars are ordinarily made with a large upper diameter which again reduces their width.

The present invention is designed to overcome this difficulty of restricted advertising space, 20 while retaining all of the advantages above noted of the usual bottle collar. It attains additional advertising space without exceeding the size limits of the bottle as above noted, and, indeed, in its preferred form, does not exceed the size 25 limits of the ordinary bottle collar.

This last objective is obtained specifically by having the bottle collar folded, the design being such that the folded portion will overlie the basic bottle collar and will be adapted to be opened by removing the collar after the bottle has 30 reached the consumer.

It is, therefore, an object of the invention to provide a bottle collar having a supplemental section adapted to be folded over the main bottle 35 collar section.

It is a further object of the invention to design this section so that when in overlapping position it will be retained snugly against the bottle collar so as not to be injured during handling, packing, and the like, of the bottle.

40 It is a further object of the invention to provide such a folded bottle collar having a lower diameter approximately equal to that of the shoulder of the bottle and an upper periphery of such size as to pass over the flange of the bottle.

45 It is a further object of the invention to provide a bottle collar of this type having an upper edge straight in at least part of its extent, to which straight portion is attached the supplemental folder or folded section, the latter being adapted to be folded about this straight edge and this edge providing a sloping top to the bottle collar whereby it may pass over the flange 50 of the bottle, but yet seat snugly about the bottle neck.

55 Other objects and advantages will appear from the following description, taken in conjunction with the accompanying drawing, in which

60 Fig. 1 is a developed view of the bottle collar

showing the shape it takes when cut out of a flat sheet of material.

Fig. 2 shows the collar folded and on a bottle.

Fig. 3 is a developed view of a modified form of bottle collar with folder.

Fig. 4 is a view of the same collar on a bottle.

Referring to Figs. 1 and 2, the device generally indicated at 10 may be cut out of a suitable flexible material such as paper. It comprises a main or collar section 11 and a supplemental or folder section 12. The collar section 11 is provided with a lower arcuate edge 13 and an upper straight edge 14. Along this upper straight edge 14 supplemental section 12 is attached.

The main bottle collar 11 provides an elongated 15 section, at one end of which there is formed a tongue 15, and at the other end is provided a slot 16 having an angular extension 17 thereon. The supplemental section 12 is here shown as 20 semicircular, its radius being desirably substantially equal to the maximum width of the section 11. A middle portion 18 of the edge 14 constitutes the junction line between sections 11 and 12 and also provides a fold line along which the section 12 may be folded so as to overlie the 25 section 11, as shown in Fig. 2.

The sections may be provided with suitable advertising matter, as is shown. Ordinarily, the back face of the section 12 when folded down, as shown in Fig. 2, may carry main advertising. 30 The inside face shown in Fig. 1 may carry the more extended information that requires careful attention.

In using the device, the supplemental section 12 is first folded down on the line 18 to overlap 35 the main collar. The tongue 15 is then engaged through the slot 16, this operation being facilitated by the presence of the extension slot 17 that also provides a certain pivotal action for a purpose to be described. The collar will then be 40 in the familiar shape of the section of a cone, the lower edge lying in a plane. The device may then be slipped over the bottle with the lower edge 13 resting smoothly about the shoulder of the bottle, as is shown in Fig. 2. The upper 45 edge being straight, will not lie precisely in a plane. It will, however, slope relative to the lower edge and it will have a periphery at least as large as the flange F on the bottle, but will nevertheless snugly seat on the bottle neck below 50 the flange. Hence, it may be dropped over this flange conveniently.

In addition, the fact that the supplemental section is caused to arch around the bottle provides 55 that this section will adhere snugly to the main bottle collar. It does not flare outwardly and, indeed, resists the effort to draw it outwardly. Consequently, it will not be damaged in packing, icing, or the like, of the bottle. It will, of course, 60

be understood that, where desired, the supplemental section 12 may be folded to the inside of the collar. In this preferred form, it also will be observed that the supplemental section is wholly contained within the limits of the whole bottle collar.

Referring to Figs. 3 and 4, there is shown a bottle collar 20 having a main section 21 and a supplemental section or folder 22. In this case, the lower edge of the collar has a straight portion 23 and arcuate portions 24 and 25. The upper edge 26 is straight and along the portion 27 thereof the supplemental section 22 is joined to the main section, the line 27 constituting a fold line. This collar is provided at one end of the section 21 with a tongue 28 and at the other end with a V-slot 29 similar to those in the first modification. The upper edge 30 of the section 22 is made to conform to that part of the lower edge 20 that it overlaps.

In use, the section 22 is folded along the line 27 to overlie the section 20. The tongue 28 is then engaged in the slot 29, whereupon the device forms itself into a portion of a cone. It will be seen that the arcuate portion 25 of the lower edge rests approximately on the shoulder of the bottle; whereas the straight portion 23 extends upwardly. The portion 25 preferably is given sufficient length to support the collar securely on the shoulder. The functioning of this device and the manner of containing the advertising may be similar to that of the first modification. This form, however, provides somewhat more advertising space. As in the first modification, the upper edge is so shaped as to pass over the flange F of the bottle and yet to permit the device to rest snugly about the tapered neck thereof.

It will be seen from the foregoing description that this invention has provided a bottle collar that attains all the compactness of the ordinary type of such collar, together with its convenient fitting over the bottle; but yet has additionally provided supplemental advertising space. The device also adheres closely to the bottle neck, so as to minimize possibility of damage. The first modification has an attractive form that quickly catches the eye and suggests the possibility of removing the tab for the information contained thereunder. The second modification attains additional advertising space and involves less loss of paper, since, in laying out bottle collars of this type on a large sheet, one can be formed on the top of the previous one. In the claims to ensue, where the term "folder" is used, it is to be understood that the same is employed in its generic sense, involving one or more sheets of any desired shape.

What is claimed is:

1. A display device adapted to fit on the neck of a tapered neck bottle, comprising a piece of flexible material including an elongated first section, the lower edge of which is convex and the upper edge of which is straight for at least part of its extent, a second section joined to said first along said straight edge and adapted to be folded to overlie said first section, and means joining the ends of said first section together to form a portion of a cone, the convex lower edge of the device becoming approximately planar when the device is so shaped, and the device being adapted to fit over the neck of the bottle with the lower edge resting adjacent the shoulder thereof, and the second section being of such extent along said upper edge as to be arched with said edge and

thereby to be maintained snugly against the first section when the device rests about the bottle.

2. A display device comprising a piece of flexible material including an elongated first section having a lower edge with a central portion and end portions extending outwardly and upwardly therefrom, and an upper edge straight throughout at least a portion of its length, a second section joined to said first section along and extending outwardly from said straight edge, said second section having an outer edge of the same contour as that of the central portion of the lower edge of the first section, and a width equal to the width of the collar at said central portion, whereby said second section may be folded to overlie said first section, and means joining the ends of said first section together to form the device into a portion of a cone, the length of the supplemental section along the straight edge being such that when the device is in conical shape, the junction between the sections is arched to prevent unfolding of the second section from the first.

3. A display device comprising a main portion consisting of an elongated piece of flexible material having an arcuate lower edge, means joining the ends of said piece together to form the device into a collar adapted to fit over the neck of a tapered bottle, the upper edge of said piece when flat being straight along a major portion, and when formed into a cone, extending a major part of the distance around the same, and a supplemental section joined to said straight edge, said junction extending along a major portion of said upper edge, whereby to be arched with the device and thereby to be maintained against the same.

4. A display device for use on the neck of a tapered neck bottle including an elongated main section having a generally arcuate lower edge, a supplemental section extending from the upper edge, joined thereto, and adapted to be folded over the main section, means joining together the ends of the main section to form the device into a collar in the shape of a portion of a cone, the base of which is defined by the generally arcuate lower edge, said collar being sized to slip over the top of the bottle and have its lower edge rest upon the tapered neck, the supplemental section being of such width on the upper edge that its ends extend a substantial distance around the collar and are displaced from the same plane to such extent that when the supplemental section is folded down, the junction between the said section with the main section maintains the supplemental section closely to the main section.

5. A bottle collar for use on the neck of a tapered neck bottle consisting of an elongated piece of flexible material shaped into a portion of a cone, the lower edge of the collar being substantially in a plane and of such size as to slip over the top of the bottle and to support the collar evenly about the bottle, the upper edge providing an opening of such size as to slip over the top of the bottle, and to be positioned around the tapered neck, an extension secured to the upper edge of the collar and folding over the same, the lateral limits of the junction of said extension with the collar being displaced from each other around the collar a substantial distance so that when folded on the collar the extension will be arched with the collar sufficiently so that the extension cannot lift from the collar when the same is fitted about the bottle.
